UNITED STATES PATENT OFFICE.

ALFRED C. EVANS, OF NORFOLK, VIRGINIA.

STEAM-BOILER.

SPECIFICATION forming part of Letters Patent No. 761,462, dated May 31, 1904.

Application filed March 26, 1901. Serial No. 52,994. (No model.)

To all whom it may concern:

Be it known that I, ALFRED CLINTON EVANS, a citizen of the United States, and a resident of Norfolk, in the county of Norfolk and State of Virginia, have made a certain new and useful Invention in Steam-Boilers; and I declare the following to be a full, clear, and exact description of the same, such as will enable others skilled in the art to which it appertains to make and use the invention, reference being had to the accompanying drawings, and to letters of reference marked thereon, which form a part of this specification.

This invention has relation to steam-boilers, and has for its object the provision, in combination with a return-flue boiler, of a water-tube lining or inclosure for the combustion-chamber, in combination with a feed-water heater and in connection with certain other features hereinafter described, for the purpose of obtaining the maximum amount of steam generation from a minimum amount of fuel, at the same time providing for durability in all parts of the boiler and with but little increased weight.

With this object in view the invention consists in the novel construction and combination of parts, all as hereinafter described, and pointed out in the appended claims.

In the accompanying drawings, Figure 1 is a front elevation of the invention. Fig. 2 is a top plan view of the same. Fig. 3 is a section on the line 3 3, Fig. 1. Fig. 4 is a section on the line 4 4, Fig. 3; and Fig. 5 is a detail sectional view of the connection of water-tubes and manifolds.

Referring to the drawings, the letter A designates the water-drums, of which two are shown arranged side by side, having a common water circulation, steam-drum, and smoke-pipe and having return fire-tubes *a a*, and B B are the separate fire or combustion chambers extending underneath said drums and communicating with said tubes through the uptakes at the rear, the accessories of such boilers being of the usual character common to return-flue boilers having the fire-bridges *b*, grates *b'*, &c. At each side of each fire-chamber, underneath the drums and extending the full length thereof from the front wall of the

furnace past the fire-bridge and arranged at each side also of the uptakes to the rear wall of the furnace, are the continuous double lines of water-tubes C C of a staggered or break-joint arrangement, such tubes extending likewise the full height of the fire-chambers and uptakes and forming, in effect, not only a water-heating surface of the maximum extent, but also effectively protecting the inner lining of the combustion-chamber from injury from excessive heat, these tubes being intermediately of their height offset or bent inwardly in a vertical plane to conform in curvature to the lower halves of the water-drums, to which they closely approach, and to form an inclosing arch over the fire-chambers, the resultant curvatures being all of a continuous downward direction and avoiding the horizontal, so as to prevent accumulation of mud, &c.

D D are bottom longitudinal manifolds arranged at the bottom of the furnace underneath said lines of tubes and to which the four-way Y-joints *d d* are connected by suitable union-couplings *d'*, the vertical lines of tubes being connected in groups of four to each said Y-joint by right and left threaded sleeves *d''* in such manner as to inclose and guard the threads of the joints from injury by the flames, which injury is further avoided by the location of said sleeves on a level with the grate-bars or the coolest part of the fire.

E E are the top longitudinal manifolds, located about on a level with the tops of the boiler-drums and above the vertical lines of pipes aforesaid, which have a similar connection therewith in groups of four.

F F are double vertical lines of water-tubes located adjacent to the rear wall of the combustion-chamber and extending the full height thereof and of the uptakes at the rear, such tubes being arched or bent forwardly at their upper portions to form a roof or cover over the uptakes and to bring such tubes in register with the upper cross-manifold hereinafter described, with which said tubes are connected in groups of four by means of right and left threaded sleeves, four-way Y-joints, and union-couplings, as hereinbefore described.

E' E' are cross-manifolds at top and bottom of the furnace and at the rear of the same,

the lower said manifold being on a level with the lower longitudinal manifolds, with which it has a free communication through suitable joints, and the upper said manifold being located somewhat above the longitudinal upper manifolds, with which it has also a free communication through suitable joints, said upper cross-manifold having also a communication with the interior of the water-drums at the top thereof by downwardly-extending elbows *ff*.

Downflow-pipes *G G* communicate with the lower forward part of the boiler-drums, such pipes being extended laterally and downwardly at the outer sides of the drums to communicate with the lower longitudinal manifolds. Such pipes *G* are also extended laterally at the inner sides of the water-drums and are united, the water-gage being connected with such inner lateral pipe extensions.

The extremities of the manifolds have suitable caps or plugs, which may be removed for cleaning purposes. The upper and lower central longitudinal manifolds *D* and *E* are common to the inner lines of pipes *C C* of both furnaces, a double arrangement of *Y*-joints, &c., being employed for this purpose.

All of the upper manifolds and the upper portions of the tubes *C* and *F* communicating therewith form an extension or supplementary steam-space of the water-drums, while the balance of said tubes and the lower manifolds form an extension or supplementary water-space of said drums.

My union-couplings consist of the two sections of pipe *Y Y*, having a threaded connection each with one of the four-way *Y*-joints and a similar connection with the manifold. One of said sections *Y* is outwardly flanged at its inner extremity and threaded upon said flange for engagement with the coupling-sleeve *Z*, having an inwardly-extending annular flange or collar *z*, engaging an inwardly-extending annular flange *y* at the inner end of the other said section *Y*, whereby upon turning said coupling-sleeve the two sections *Y Y* are drawn together, a suitable packing being arranged between their abutting ends. It is therefore obvious that by disconnecting the pipe-sections *Y Y* through the union-couplings the water-tubes may be removed in whole or in part in groups or nests of four and as readily replaced in the same manner, or by turning threaded sleeves *d* any single pipe may be removed.

I will now describe my feed-water heater, as follows: *H H* are longitudinal horizontal lines of tubes arranged adjacent to the side walls of the combustion-chamber and inside of the swells of the lines of water-tubes *C C* and communicating at their extremities to form a coil at each side of the furnace, the top members of such coils being extended upwardly at their rear ends and then forwardly to connect with the interior of the boiler-drums

and the lower members of said coils being extended forwardly through the forward wall of the furnace and then laterally and upwardly to connect with the feed-water pump.

Having thus described my invention, what I claim as new, and desire to secure by Letters Patent, is—

1. In a return-flue steam-boiler, the water-tubes inclosing the combustion-chamber below the water-drum, and having an inward extension or offset over said chamber, and the water-tubes inclosing the uptake at the rear of said drum, and having an inward extension or offset over the said uptake, substantially as specified.

2. In a return-flue steam-boiler, the two lines of water-tubes, having a break-joint arrangement, and inclosing the combustion-chamber thereof, and having an inward extension over said chamber to form a cover therefor, substantially as specified.

3. In a return-flue steam-boiler, the water-tubes inclosing the combustion-chamber below the water-drum, and having an inward extension or offset over said chamber to form a roof or cover therefor, and the feed-water tubes at the sides of said chamber, and lying within the offset portions or inward extensions of said first - named tubes, substantially as specified.

4. In a return-flue steam-boiler, the upper and lower longitudinal manifolds, the vertical water-tubes connected to said manifolds at top and bottom, and lining the sides of the combustion-chamber below the water-drum, and the sides of the uptake at the rear thereof, the upper and lower cross-manifolds, the vertical water-tubes lining the rear of said chamber, and of said uptake, and connected to said cross-manifolds at top and bottom, and the downflow-pipe connecting the lower forward portion of the boiler-drum with said lower manifolds, substantially as specified.

5. In a steam-boiler, the return-flue horizontal water-drums, having a common steam-drum, a common water circulation, and a common smoke-pipe, the vertical water-tubes, inclosing the combustion - chambers of said boiler, the lateral of said vertical tubes having an inward swell close to the water-drums, and over said chamber, and the rear said vertical tubes having an inward extension over the uptakes, the upper and lower longitudinal and cross manifolds, with which said tubes are connected at their extremities, and the downflow-pipes connecting the lower forward portions of the water-drums with said lower manifolds, substantially as specified.

In testimony whereof I affix my signature in presence of two witnesses.

ALFRED C. EVANS.
